UNITED STATES PATENT OFFICE.

GEORGE D. JAMES, OF FRANCES, WASHINGTON.

WIRE-CUTTER.

1,147,631.

Specification of Letters Patent. Patented July 20, 1915.

Application filed November 28, 1914. Serial No. 874,489.

To all whom it may concern:

Be it known that I, GEORGE D. JAMES, a citizen of the United States, residing at Frances, in the county of Pacific and State 5 of Washington, have invented certain new and useful Improvements in Wire-Cutters; and I do hereby declare the following to be a full, clear, and exact description of the invention, such as will enable others skilled 10 in the art to which it appertains to make and use the same.

This invention relates to wire cutters and the primary object of the invention is the provision of a wire cutter for attachment to 15 the barrel supporting section of a rifle stock for use by soldiers for cutting wires which might impede their forward marching or advance.

Another object of this invention is to provide a wire cutter as specified which has the hand grip portion of the operating lever insulated, and also suitable insulations associated therewith for insulating the cutter from the barrel of the gun so as to prevent 20 the electrocution of the person carrying the gun when cutting charged electric wires.

With the foregoing and other objects in view this invention consists in such novel features of construction, combination and 30 arrangement of parts as will be hereinafter more fully described, illustrated in the accompanying drawings and claimed.

In describing the invention in detail, reference will be had to the accompanying 35 drawings wherein like characters designate like or corresponding parts throughout the several views, and in which:—

Figure 1 is a side elevation of the improved wire cutter, showing the same applied to an ordinary military rifle, Fig. 2 is a bottom plan view of the wire cutter, showing a fragment of the rifle to which the same is attached, Fig. 3 is an enlarged side elevation of the wire cutter, Fig. 4 is an enlarged side elevation of the wire cutter, showing the same in an open position prior to the cutting of a wire, Fig. 5 is a cross sectional view on the line 5—5 of Fig. 1, Fig. 6 is a cross sectional view on the line 6—6 of Fig. 2, Fig. 7 is a detail perspective view of a part of the construction of the wire cutter, Fig. 8 is a detail perspective view of the cutting or shearing knife of the wire cutter, and Fig. 9 is a cross sectional view 55 on the line 9—9 of Fig. 8.

Referring more particularly to the draw-

ings, 1 designates an ordinary military rifle, which has the forwardly projecting barrel supporting section 2 formed thereupon, which barrel supporting section is formed of 60 wood, as is ordinary in the construction of rifles of this nature.

The barrel supporting stock 2 of the rifle 1 is provided with a recess 3 formed in the under surface thereof, which is provided for 65 receiving a handle or operating lever 5 of the wire cutting stretcher 6. The handle lever 5 is substantially semi-circular in cross section, as is clearly shown by reference to Fig. 7 of the drawing, so as to fit snugly 70 within the recess 3 and so as to conform to the curvature of the under surface of the barrel support 2. The handle lever 5 is pivotally connected at 7 to a substantially U-shaped bracket 8 which has its upper connected end mounted upon the upper surface 75 of the barrel 9 of the rifle and extending downwardly therefrom, as is clearly shown by reference to the drawings. The U-shaped supporting bracket 8 is insulated 80 from the gun barrel by a plate of insulation 10. The hand lever 5 has a projection 11 formed upon its forward or outer terminal end, which is of reduced width to the width of the hand lever and is pivotally connected 85 at 12 to a link 13. The link 13 is in turn pivotally connected at 14 to the shear or cutting lever 15 of the wire cutter 6. The shear or cutting lever 15 is pivotally connected at 16 to the gun barrel supporting section 2 90 and it has its end 17 which projects outwardly toward the end of the gun barrel from a pivotal point 16 provided with a cutting or shearing edge 18 which coacts with a shearing or cutting edge 19 formed upon 95 a stationary cutting blade 20.

The stationary cutting or shearing blade 20 is substantially U-shaped in cross section and is beaded in a recess 21 which is formed in the barrel supporting stock 2. The shearing or cutting edge 19 is formed upon one side of a supporting structure 20 and projects tangentially therefrom, having its outer surface positioned substantially in a vertical plane and parallel with the inner 100 surface of the cutting end 17 of the blade 15, so that when the two blades pass each other, a shearing or cutting action will be generated for cutting wire or analogous material. The substantially U-shaped shearing or cutting blade 20 is connected in a 105 stationary manner to the rifle structure 1 by

a strap 22 which extends about the rifle barrel 9 and the barrel supporting stock 2 and is insulated therefrom by a plate 23 of insulation.

5 The extreme inner end or the end which projects toward the gun stock 25, of the handle 5, is constructed of insulation, such as hard rubber, glass or the like, as shown at 26, so as to prevent the electrocution of 10 the operator of the wire cutter when cutting electrically charged conducting wires.

The barrel supporting stock 2 has a catch 40 slidably mounted therein, which is provided for engaging the outer surface of the 15 end of the lever 5, for preventing accidental pivotal movement of this lever.

From the foregoing description taken in connection with the accompanying drawings 20 the advantages of construction and of the method of operation of the improved wire cutters will be readily apparent to those skilled in the art to which this invention appertains and, while in the foregoing description, the principle of the operation 25 of this invention has been described together with various features of construction, it is to be understood that certain minor features of construction, combination and arrangement of parts may be altered to suit practical conditions provided such alterations 30 are comprehended within the scope of what is claimed.

What is claimed is:—

1. The combination with an ordinary rifle 35 embodying a forwardly extending barrel supporting stock, said stock being provided with a recess formed in the under surface thereof, of a wire cutting structure embodying a hand lever of substantially semi-circular cross section, pivotally connected to 40

said barrel supporting stock for seating in said recess, a shearing blade pivotally connected to said barrel supporting stock, a link connecting said shearing knife and said hand lever for increasing the leverage of 45 said handle and said shearing blade upon pivotal movement of said handle, a substantially U-shaped stationary shearing blade supported by the barrel supporting stock and having a cutting blade projecting tangentially therefrom for coacting with said pivoted shearing blade.

2. The combination with an ordinary rifle embodying a forwardly extending barrel supporting stock, said stock being provided 55 with a recess formed in the under surface thereof, of a wire cutting structure embodying a hand lever of substantially semi-circular cross section pivotally connected to said barrel supporting stock for seating in 60 said recess, a shearing blade pivotally connected to said barrel supporting stock, a link connecting said shearing knife and said hand lever for increasing the leverage of said handle and said shearing blade upon 65 pivotal movement of said handle, a substantially U-shaped stationary shearing blade supported by the barrel supporting stock and having a cutting blade projecting tangentially therefrom for coacting with said 70 pivoted shearing blade, said hand lever and said shearing blade being insulated from the barrel of said rifle.

In testimony whereof I affix my signature in presence of two witnesses.

GEORGE D. JAMES.
